UNITED STATES PATENT OFFICE

2,441,312

ELECTRICAL INDUCTION HEATER FOR
CARBURETORESWilliam N. Dickerson, Sullivan, Ind., and
Lucas D. Gonzales, El Paso, Tex.

Application April 5, 1946, Serial No. 659,694

1 Claim. (Cl. 219—38)

1

This invention relates to an electrical induction heater for aircraft carburetors, and more particularly to such a device for use in conjunction with pressure injection type aircraft carburetors.

A primary object of this invention is the provision of a device adapted to prevent the formation of carburetor ice, and to remove the same, in the event that such ice is formed.

An additional object of the invention is the provision of such a device which will minimize engine power loss caused by the operation of the apparatus.

Still a further object of the invention is the provision of such a device adapted to heat the carburetor in such manner as substantially to eliminate any fire hazards which might be occasioned thereby.

A further object of the invention is the provision of such a device which may be readily applied to any conventional carburetor, and which will be effective under a wide variety of conditions and circumstances.

Still another object of the invention is the provision of such a device which will be sturdy and durable in construction, reliable and efficient in operation, and relatively simple and inexpensive to manufacture, assemble, and install.

Other objects reside in the combinations of elements, arrangements of parts, and features of construction, all as will be more fully pointed out hereinafter and disclosed in the accompanying drawing, wherein there is shown a preferred embodiment of this inventive concept.

In the drawings:

Figure 1 is a longitudinal sectional view taken substantially through the center line of a conventional carburetor for aircraft.

Figure 2 is a top plan view of a portion of the apparatus, certain parts thereof being omitted.

Figure 3 is a top plan view of an additional portion of the apparatus.

Similar reference characters refer to similar parts throughout the several views of the drawings.

As conducive to a clearer understanding of this invention, it may here be pointed out that heretofore methods of preventing carburetor ice have been developed, but the conventional anti-ice and de-ice methods are unsatisfactory. In alcohol anti-ice systems, it has frequently been observed that so much alcohol is lost by leakage as to render the device inoperative, and that such leakage provides a major fire hazard. Further, previously devised air heating systems are ineffective unless

applied prior to entering an icing area, and as only a skilled meteorologist can anticipate all icing conditions, such precaution has frequently not been taken. If an air heating system is applied after ice is indicated by loss of power, the cylinder heat is seldom sufficient to remove the ice.

Experimentation has disclosed that in icing of the carburetor the entire air scoop does not freeze. This is indicated by the fact that the manifold pressure would drop materially, and this has not with repeated experiments been indicated. It follows, therefore, that since the engine supply of air remains adequate, failure is caused by the lack of fuel. Since the amount of fuel metered to the engine depends upon the volume of air rushing through the carburetor, it follows that engine failure is occasioned because the boost venturi and impact tubes are iced over. An important object of this invention is, therefore, the provision of a means to preclude the formation of ice in the boost venturi and the impact tubes, and thus preclude failure due to carburetor ice.

Having reference now to the drawings, there is generally indicated at 10 an air scoop of an aircraft carburetor, including a main Venturi throat 11 having positioned therein a plurality of radially positioned impact tubes 12. The tubes 12 communicate with an air chamber 13 positioned between the wall of the device and the venturi.

As is customary, the device includes a booster venturi 14 mounted on a suitable supporting bracket 15, and having an exteriorly positioned shoulder 16. A conventional butterfly valve 27 and control rod 28 therefor is also provided.

It may here be pointed out that in the customary operation of such device, air enters the boost venturi and simultaneously the impact tubes 12. The difference in pressure between the space 13 into which the impact tubes 12 enter, and the pressure in the boost venturi 14 controls the movement of the poppet valve which controls in turn the amount of fuel released into the discharge pipe. The structure heretofore described has been conventional, and the instant invention comprises the positioning of a coil of wire 17 about the boost venturi 14, and an additional coil of wire 18 adjacent the inlet of the impact tubes. In the preferred embodiment of the invention, alternating current is applied from a conventional aircraft inverter of the 26 volt 400 cycle alternating type, to the coils 17 and 18, whereby to heat the metal venturi 11 and the

booster venturi 14 in a well known manner without heating the coils 17 and 18 themselves.

The temperatures to which the venturi 11 and booster venturi 14 are heated is dependent upon the number of ampere turns of the coils 18 and 17, and, to some extent, upon the rate at which heat is lost by being extracted by air passing through the venturis. However, we have found that such heat loss is minor, and that a sufficiently high temperature may be maintained despite any variations in air temperature or moisture content of the air.

Cockpit control for the device may be readily provided by the use of a suitably positioned single throw switch and a warning light wired in parallel in a known manner.

While in the foregoing the application of the device has been indicated in association with a carburetor of conventional type, it is to be noted that the carburetor may be wired as manufactured and equipped with a suitable quick disconnection plug (not shown) for ease of maintenance. Obviously, the carburetor may be wound in a different manner from that herebefore disclosed in order to accommodate different types of carburetors.

From the foregoing it will now be seen that there is herein provided an improved apparatus, accomplishing all the objects of this invention, and others, including many advantages of great practical utility and commercial importance.

As various embodiments may be made of this inventive concept, and as various modifications

may be made in the embodiment hereinbefore shown and described, it is to be understood that all matter herein is to be interpreted merely as illustrative and not in a limiting sense.

5 We claim:

In a de-icing carburetor for aircraft including a source of high frequency electric current, the combination with a primary Venturi tube in said carburetor, impact tubes connected to said 10 primary venturi, and a booster venturi concentrically disposed relative to said primary venturi, said tubes all being formed of current-conducting material; of separate high frequency induction coils concentrically disposed about both of 15 said Venturi tubes for rapidly and inductively heating the same and said impact tubes to relatively high temperatures to prevent the formation of ice in said Venturi tubes and said impact tubes.
